DRESS

Helen Lee Caldwell, New York, N. Y., assignor to Wohl & Company, Inc., New York, N. Y., a corporation of New York

Application October 8, 1949, Serial No. 5,370

Term of patent 3½ years

(Cl. D3—26)

To all whom it may concern:

Be it known that I, Helen Lee Caldwell, a citizen of the United States of America, and a resident of New York, in the county and State of New York, have invented a new, original, and ornamental Design for a Dress, of which the following is a specification, reference being had to the accompanying drawing, forming a part thereof, in which—

Fig. 1 is a front elevational view of the dress, showing my new design; and

Fig. 2 is a rear elevational view thereof.

I claim:

The ornamental design for a dress, as shown.
